US00D849817S

(12) **United States Design Patent** (10) Patent No.: **US D849,817 S**
(45) Date of Patent: **** May 28, 2019**

(54) **DRIVING RECORDER DEVICE**

(71) Applicants: **HONGFUJIN PRECISION ELECTRONICS(CHONGQING)CO. LTD**, Chongqing (CN); **HON HAI PRECISION INDUSTRY CO., LTD.**, New Taipei (TW)

(72) Inventors: **Yi-Wen Wang**, New Taipei (TW); **Chih-Kang Cho**, New Taipei (TW); **Mei-Hua Liu**, Shenzhen (CN)

(73) Assignees: **HONGFUJIN PRECISION ELECTRONICS (CHONGQING) CO., LTD.**, Chongqing (CN); **HON HAI PRECISION INDUSTRY CO., LTD.**, New Taipei (TW)

(**) Term: **15 Years**

(21) Appl. No.: **29/585,906**

(22) Filed: **Nov. 30, 2016**

(57) **CLAIM**

The ornamental design for a driving recorder device, as shown and described.

DESCRIPTION

FIG. 1 is a front perspective view of a driving recorder device;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines depict portions of the driving recorder device in which the design is embodied that form no part of the claimed design.
